GARDENING HOE

William M. Davidson, 648 Auburn, Tulare, Calif.

Filed Sept. 23, 1964, Ser. No. 31,856

Term of patent 14 years

(Cl. D35—2)

FIG. 1 is a view in side elevation of the gardening hoe showing my new design.

FIG. 2 is an enlarged top plan view of the hoe with the handle member fragmentarily shown for convenience of illustration.

FIG. 3 is a view in side elevation of the hoe as illustrated in FIG. 2.

FIG. 4 is a view in front elevation of the hoe.

FIG. 5 is a perspective view of the hoe.

The dominant features of my design reside in the portions shown in full lines.

I claim:

The ornamental design for a gardening hoe, as shown and described.
